(57) **CLAIM**

The ornamental design for a watch face, as shown and described.

DESCRIPTION

FIG. 1 is a front perspective view of the watch face of the present invention;

FIG. 2 is a front elevational view thereof; and,

FIG. 3 is another front perspective view thereof.

The broken lines, where used in FIGS. 1-3, are for illustrative purposes only and form no part of the claimed design.

1 Claim, 3 Drawing Sheets
